UNITED STATES PATENT OFFICE

2,541,914

CARTON FOLDING MACHINE

Hugh F. Conser, Detroit, Mich., assignor to
Shedd-Bartush Foods, Incorporated, Detroit,
Mich., a corporation of Michigan

Application May 14, 1945, Serial No. 593,639

2 Claims. (Cl. 93—49)

1

The present invention relates to a machine for squaring and closing one end of the type of cardboard carton which has four walls permanently connected together at parallel fold lines to form a closed parallelogram and in which each of the ends is closed by four foldable flaps, two of which fold toward each other from opposite sides of the carton and are connected together by the entry of a hook formed in one of the flaps into a slot formed in the other.

Cartons of the above type which are used for packaging ice cream and similar materials are shipped in a flattened condition which is achieved by simply collapsing the parallelogram formed by the four permanently connected sides. When the carton is to be filled, it is necessary to square up the parallelogram and close one end of the carton. Because of the construction of the box it is necessary that it be completely squared before the flaps, having the co-operating hook and slot, are folded into position. Up to date no one has succeeded in developing a commercially usable machine for automatically squaring and closing one end of such a carton, and consequently, although millions of such cartons are used, it has been necessary to square and close one end by hand preparatory to filling. This is a slow, tedious, and expensive operation.

Accordingly, it is the general object of the present invention to provide an automatic machine for squaring and closing one end of a carton of the type mentioned.

Another object of the invention is to provide a machine of the type mentioned, which is rugged and simple in construction and foolproof and rapid in operation.

Another object of the invention is to provide an improved means for folding and interlocking a pair of oppositely positioned flaps provided respectively with a hook and slot when the fold lines of the two flaps extend parallel to each other at the time of folding.

Another object of the invention is to provide an improved means for opening the slot in the slotted flap so that the insertion of the hook on the interlocking hooked flap will be facilitated.

Another object of the invention is to provide an improved squaring means for a carton of the type described.

Another object of the present invention is to provide a machine of the type mentioned incorporating an improved carton feeding mechanism.

A further object of the invention is to provide an improved machine of the type mentioned in

2

which substantially all of the moving parts of the machine are driven from a single camshaft.

Another object of the invention is to provide a machine of the type mentioned having a removable end closing head, the operating mechanism of which is so connected to the permanent parts of the machine as to facilitate removal of the head and substitution of another head adapted to operate upon a different size carton.

10 Other objects of the invention will become apparent from the following specification, the accompanying drawings, and the appended claims.

In the drawings,

Figure 1 is a side elevation of the machine with parts broken away;

Figure 2 is a plan view of the machine with parts of the operating linkages removed to facilitate illustration of the remaining structure;

Figure 3 is a fragmentary longitudinal section taken on the line 3—3 of Figure 2;

Figure 4 is a fragmentary section taken on the line 4—4 of Figure 1;

Figure 5 is an enlarged fragmentary elevation taken on the line 5—5 of Figure 2, showing one side of the end closing head;

Figure 6 is a fragmentary section on the line 6—6 of Figure 1;

Figure 7 is a fragmentary section taken on the line 7—7 of Figure 2;

30 Figure 8 is a longitudinal section of the end of the main feed pusher showing on an enlarged scale that portion of the mechanism indicated by the circle E, in Figure 1;

Figure 9 is a fragmentary transverse section taken on the line 9—9 of Figure 1, illustrating the operating linkage for a portion of the hooked flap closing mechanism;

Figure 10 is a fragmentary transverse section taken on the line 10—10 of Figure 1 showing the operating linkage for the top flap closing mechanism;

Figure 11 is a fragmentary transverse section taken on the line 11—11 of Figure 1 showing the operating linkage for the carton backup and end spreading member;

Figure 12 is a transverse section taken on the line 12—12 of Figure 1 showing the operating linkage for the hooked flap flattening element;

50 Figure 13 is a fragmentary section taken on the line 13—13 of Figure 1 showing the operating linkage for the slotted flap closing member;

Figure 14 is a fragmentary section taken on the line 14—14 of Figure 1 showing the operating linkage for the slot piercing blade;

Figure 15 is a fragmentary section on the line 15—15 of Figure 14;

Figure 16 is a fragmentary section taken on the line 16—16 of Figure 1 showing the operating linkage for the bottom flap closing member and the slotted flap backup member;

Figure 17 is a fragmentary section taken on the line 17—17 of Figure 1 showing the operating mechanism for the final squaring device;

Figure 18 is a perspective view showing one end of the type of carton upon which the machine is adapted to operate;

Figure 19 is an elevation view of a carton collapsed flat in the form in which it is shipped, showing the manner in which the magazine feed dog shifts a carton into the path of movement of the main feed pusher;

Figure 20 is a fragmentary longitudinal section looking from the magazine side of the machine and showing the initial position of the carton spreading blade;

Figure 21 is a view similar to Figure 20 showing the carton spreading blade after it has entered the carton to the full extent;

Figure 22 is an end elevation taken on the line 22—22 of Figure 21;

Figure 23 is a view similar to that of Figure 22 showing the condition of the carton after it has entered the final squaring device but before the final squaring device is operated;

Figure 24 is a view similar to Figure 23 showing the condition of the carton after the final squaring device has completed its operation;

Figure 25 is a fragmentary longitudinal section through the folding head showing the closed positions of the backup and end spreading device and the top flap folding member;

Figure 26 is a view similar to Figure 25, showing the closed position of the bottom flap closing member and the upper position of the slotted flap backup element;

Fig. 27 is a side elevation of the carton within the folding head showing the manner in which the slot pierce blade co-operates with the slotted flap backup element to open the slot;

Figure 28 is a view similar to Figure 27 showing the closed position of the slotted flap closing member;

Figure 29 is a perspective view of the end of the carton within the folding head showing the beginning of the hooked flap folding operation;

Figure 30 is a fragmentary section taken on the line 30—30 of Figure 29;

Figure 31 is a perspective view similar to Figure 29 showing an intermediate stage in the hooked flap folding operation just prior to entry of the hook into the slot and the slotted flap; and

Figure 32 is a perspective view similar to Figures 29 and 31, showing the final hooked flap folding operation and the beginning of the carton ejecting operation.

In Figure 18 of the drawings is illustrated one end of the type of carton upon which the machine of the present invention is adapted to operate. As there shown, the carton comprises a bottom wall *a*, top wall *b*, and a pair of side walls *c* and *d*. A flap *e*, integral with the bottom wall *a*, overlaps the side wall *d* and is permanently secured thereto in any desired manner, as by gluing, prior to shipment of the carton to the user. The resulting carton is in the form of a quadrilateral parallelogram which may be collapsed flat for shipment. When the carton is to be used it must be squared up; that is to say, the angles between the sides *a*, *b*, *c*, and *d*, must be 90 degrees,

whereupon the ends may be closed. The present machine operates to square the carton and close one end in preparation for filling.

Since the closing flaps are the same at both ends, only one end is illustrated in Figure 18. As there shown, the end of the carton is closed by four flaps; namely, a bottom flap *f*, a top flap *g*, and side flaps *h* and *j*. The flap *h* is provided with a slot *k* adapted to receive a hook *m* formed on the flap *j*. Since the flaps *f* and *g* must be folded before the flaps *j* and *k*, the box must be square when the flaps *j* and *h* are folded.

Referring to the drawings, and particularly to Figures 1, 2, 3, and 4 thereof, the machine is provided with a base frame indicated generally by the numeral 1, which may be of any desired construction. As illustrated, it comprises a lower floor 2 adapted to support a motor 3, which is connected by a belt to a speed changer 4 of any desired construction. The speed changer 4 may, for example, be a Reeves' drive. The speed changer 4 is connected by means of a belt to a pulley on a cross shaft 7. The cross shaft carries a bevel gear 8 which is in mesh with a bevel gear 9 on a longitudinally extending camshaft 10. The camshaft 10 is supported on bearings 11, 12, and 13 which rest respectively on transverse frame members, 14, 15, and 16 carried by a pair of upper longitudinal rails 17 constituting a portion of the base frame 1.

The top framework of the machine comprises a pair of longitudinally extending top rails 18 and 19 of channel construction, as best shown in Figures 1 and 4, which are connected together by cross-connecting members 20 and 21. The rails 18 and 19 are supported adjacent their left-hand ends by a pair of inclined angle iron supporting members 22 and at their right-hand ends by a pair of inclined channel members 23, the supporting members 22 and 23 being secured in any suitable manner to the base frame.

As best shown in Figures 2 and 4, an auxiliary frame 24 is secured to the longitudinal channel 19 and is supported by an auxiliary strut 25 in a position projecting transversely to the rails 18 and 19. Supported upon the frame 24 is a magazine 26 which may be of any desired form or construction adapted to receive a stack of collapsed cartons indicated in dotted lines in Figure 4 by the numeral 27. The cartons within the magazine rest upon a plurality of longitudinally extending strips 28 upon which the lowermost carton is adapted to slide when ejected from the magazine. As best shown in Figures 2 and 7, a magazine ejector slide 29 is slidably positioned in suitable ways formed in the frame 24 for movement in a direction transversely to the channels 18 and 19. The ejector slide 29 carries an ejector dog 30 having a pair of spaced raised knifelike projections at its forward edge adapted to enter between the lowermost carton and the carton which rests thereon when the dog 30 moves to the left, as viewed in Figure 4. During ejection of the lowermost carton by the dog 30 a pivoted stop 31 carried by the magazine operates to prevent ejection of more than one carton at a time. The pivoted stop 31 is resiliently held in the position illustrated in the drawings by means of a leaf spring 32 shown best in Figures 3 and 4. The spring 32 permits yielding of the stop 31 in response to any excessive forces which might otherwise injure the mechanism. The space between the two knifelike projections on the ejector dog permits the dog to pass beyond the stop 31.

The ejected carton is held flat by a pair of leaf

springs 33 against the top surfaces of a pair of longitudinally extending top plates 34 and 35 which are secured to the top flanges of channels 18 and 19 and extend for the major portion of the length of the machine. A pair of longitudinally extending angle irons 36 and 37 are secured respectively to the plates 34 and 35 and are held in spaced relation to the latter by means of a pair of longitudinally extending spacing strips 38 and 39, as best shown in Figure 4. The top flanges of the angle irons 36 and 37, together with the strips 38 and 39 and the top plates 34 and 35, provide a guideway for a main carton feeding slide 40. A longitudinally extending strip 41 is secured to the feeding slide 40 and forms part thereof. Strip 41 fills the gap between the plates 34 and 35, in order to provide a smooth surface for the reception of cartons ejected from the magazine. A similar strip 41a is fastened to the left-hand end of slide 40, as viewed in Figure 1, and projects beyond the end of slide 40.

A pair of carton engaging feed dogs 42 and 43 are mounted on the top strips 41 and 41a of the main feed slide in spaced relation to each other in position to simultaneously engage the bottom flap *f* of two successive cartons. The left-hand extremity of the strip 41 of the main feed slide, as viewed in Figures 1 and 8, is provided with a pivoted carton discharge dog 44 having a spring 45 normally urging it into an upwardly inclined position, as illustrated in Figure 8.

The machine is provided with a carton opening blade 46 which is pivotally mounted upon a pin 47 carried by a lug 48 fixed to the feed slide 40, as best shown in Figure 3. The carton opening blade projects upwardly through a suitable slot formed in the longitudinal plate 35, as best shown in Figure 2. A spring 49, fixed to the lug 48 at one end and bearing upon a projection formed on the side of the carton opening blade 46, normally urges the blade 46 upwardly about its pivot pin 47. A roller 50 journaled on the side of the carton opening blade limits its upward movement under the influence of spring 49 by engaging the lower edge of the angle iron 37, as best shown in Figure 3. This pivotal connection of the blade 46 enables it to swing downwardly as it moves to the right, as viewed in Figure 3, and passes beneath a carton lying on the plates 34 and 35 in front of the magazine 26.

A sloping block 51 is mounted at one side of the longitudinal plate 35 immediately adjacent the slot for the carton opening blade 46 in such position that when the forwarding dog 42 advances a carton to the left along the plates 34 and 35 one side wall of the carton will be lifted in the manner hereinafter set forth in greater detail to partially square the folded carton. Thereafter the folded carton is engaged by a squaring device 52 in the form of a plate bent intermediate its ends to form a right angle and having one edge pivotally secured to the upper flange of the channel 19, as best shown in Figures 2, 3, and 17.

During the squaring operation and the feeding of the cartons along the plates 34 and 35, one edge of each carton is engaged by a guiding angle iron 53, shown best in Figures 3 and 4. After a carton is fed from the squaring device 52 it passes into a one-piece guide member comprising a horizontal guide plate 54 and a vertical guide plate 55, the forward edges of which flare upwardly and outwardly, respectively, in order to insure that the flaps on the advancing end of the carton will enter the space between the plates 54 and 55 and the angle iron 53.

After passing the guide plates 54 and 55, the carton is fed into a folding head indicated generally at 56. This head comprises a base plate 57 carried by a pair of detachable supporting arms 58 which, as best shown in Figures 1 and 5, are removably secured to the longitudinal channels 18 and 19 by means of bolts or other suitable fastening device. A pair of cross bars 59 rest directly upon the top edges of the arms 58 and directly engage and support the base plate 57. The head is provided with a pair of side walls 61 extending longitudinally of the machine and a top guard or wall 62 overlying the left-hand end of the head, as viewed in Figures 2 and 3.

Suitably supported on the removable folding head are a number of elements adapted to perform the successive operations required to close the right-hand or trailing end of the carton, as viewed in Figures 1, 2, and 3. These include backup and spreader element 63 fixed to an arm 64 carried by a pivot pin 65, which is journaled in a pair of uprights 66 secured to the folding head. The backup and spreader member is formed of sheet metal and flares outwardly in the manner best indicated in Figures 1 and 2, so that as it enters the left-hand open end of the carton it spreads the four flaps at that end and also serves as a support, preventing movement of the carton under the influence of the flap closing elements hereinafter described.

The head also includes a top flap closing element 67 mounted on a pivot pin 68 which is journaled in supporting block 69 carried by the upper edges of side walls 61. A bottom flap closing element 70 is similarly carried by pivot pin 71 journaled in supporting blocks 72, in the manner best shown in Figure 5. It will be noted that the bottom flap closing element is divided into two sections which are transversely spaced so that they may pivot upwardly on opposite sides of the feed slide element 41a, as best shown in Figures 2 and 16. Fixedly secured to the bottom flap closing element is a plate 73 which is adapted to move upwardly upon closure of the bottom flap into a position inside of the adjacent side flap of the carton in which position it acts as a backup member to support the side flap during the subsequent slot piercing operation. It will be noted that the plate 73 is provided with an opening 74 to permit penetration of the slot piercing blade hereinafter described. As best shown in Figure 2, it will be seen that the guide plate 54 is slotted at 75 to permit passage of the backup plate 73. The corresponding corner of the longitudinal plate 35 is similarly cut away for the same purpose. It may be noted further that the longitudinal plates 34 and 35 terminate just short of the extremities of the bottom flap closing element 70.

A slot piercing blade 76 for piercing and opening the slot in the slotted flap is pivotally mounted on a shouldered bolt 77 which, as best shown in Figure 5, is threaded into a bent plate 78. Plate 78 is secured to the upper end of a bracket 79 by means of a screw 80. The bracket 79 is welded or otherwise fixed to one of the arms 58 which support the folding head.

A folding element 81 for the slotted flap is pivoted on a pin 82 which, as best shown in Figure 16, is carried by the previously mentioned blocks 69 and 72. As best shown in Figures 1, 2, 9, and 29 through 32, a folding element 83 for the hooked flap is pivotally mounted upon a pin 84, the upper end of which is journaled in a bracket 86 carried by a supporting member 87.

which rests upon the top edge of one of the side wall members 61. The lower end of the pin 84 is journaled in a bracket 85 fixed to the forward edge of the same side wall member 61. An edge retaining element 88 for the hooked flap is likewise freely journaled upon the pin 84 for movement thereon independently of the flap folder 83. The edge retaining element 88 is provided with a slot 89 through which projects a pin 90 fixed to the flap folder 83, as best shown in Figures 29, 30, and 31. A spring 91 carried by a spring supporting lug 92 on the element 88 passes through a suitable opening in the pin 90 and operates to pivot the edge retainer 88 about the pin 84 in advance of the flap folder 83. Consequently, the flap folder 83 drives the edge retainer 88 through the spring 91, and the slot 89 permits a relative lost motion between the elements 83 and 88.

A flattening element 93 for the hooked flap is pivoted on a pin 94, the upper end of which is journaled, as best shown in Figure 32, in the aforementioned bracket 85, while the lower end of the pin 94 is journaled in a block 95.

The elements of the machine so far described constitute all of the elements which engage and act upon the cartons during the folding operation, and the means hereinafter described serves to operate the above described mechanism in the desired manner and sequence.

The main feed slide 40 is operated by an eccentric closed cam 96 fixed to the shaft 1. The cam 96 is provided with an eccentric slot 97 which receives a roller 98 journaled on a lever 99. The lever is pivoted on a pin 100 carried by a bracket 101 fixed to the base frame of the machine. The upper end of the lever 99 is connected to the aforementioned lug 48 on the feed slide 40 by means of the pivoted link 102, shown in Figure 3.

As best shown in Figures 4 and 7, a cam 103 on the camshaft 10 is connected to and operates the magazine feed slide 29 by means of a lever 104. The lever is pivoted on a pin 105 carried by a fixed bracket 106, which is secured to one end of the frame members 17. A roller on the lower end of the lever 104 operatively engages the cam 103, and the upper end of the lever 104 is connected by a pivoted link 109 to a lug 110 secured to the underside of the magazine feed slide 29. A spring 107 having one end fixed to the lever 104 and its opposite end connected to a bracket 108 operates to hold the roller on the lever 104 in engagement with the cam 103 at all times.

A pair of longitudinally extending I-beams 111 and 112 rest upon the top surfaces of the cross members 14 and 15 in the manner best shown in Figures 2 and 9 through 17. These beams support the cam operated levers which actuate the remaining portions of the mechanism. Thus, as shown in Figure 17, cam 113 on a camshaft 10 engages a roller 114 on a lever 115, which is pivoted on a pin 116 carried by a bracket 117 supported on the I-beam 112. The roller 116 is held in engagement with the cam by spring 118 having one end connected to the lever 115 and the other to a bracket 119 fixed to the inclined supporting member 22. The upper end of the lever 115 is connected to the squaring device 52 by means of a pivoted lever 120.

As best shown in Figure 10, a cam 121 on the camshaft 10 engages a roller 122 journaled on a lever 123 which is pivoted upon a pin 124 carried by the bracket 125 secured to the I-beam 111. The roller 122 is held in engagement with cam 121

by means of a spring 126 having one end fixed to the lever 123 and the opposite end fixed to a bracket 127 carried by the I-beam 111. The lever 123 is connected to a pivoted link 128 which in turn is connected to a bell crank 129 carried by a pin 130. A pivoted link 131 connects the bell crank to an arm 132 fixed to the top flap folding element 67, as best shown in Figure 5.

A cam 133 on the camshaft 10 engages a roller 134 journaled upon a lever 135. The lever is pivoted by a pin 136 on a bracket 137 carried by the I-beam 111. The roller 134 is held in engagement with the cam 133 by spring 138 having one end connected to the lever 135 and the other to a bracket 139 fixed to the I-beam 111. As best shown in Figures 3 and 16, the lever 135 is connected by a pivoted link 140 to a bell crank 141. The bell crank is journaled on a pin 142 carried by a bracket 143 fixed to the channel member 19. The bell crank 141 is connected by means of a pivoted link 144 to an arm 145 fixed to the bottom flap folding element 70.

A cam 146 is provided on the camshaft 10 for operating the slot piercing blade 76. This cam 25 is a face type cam having a single relatively sharp projection 147, as best shown in Figure 15. As shown in Figure 14, the cam 146 engages a roller 148 on a lever 149 which is pivoted on a pin 152 carried by a bracket 153 on the I-beam 112. The roller 148 is held in contact with the cam 146 by means of a spring 153, one end of which is connected to the lever and the other to a bracket 151 carried by the I-beam 112, as best shown in Figure 1. The upper end of the lever 149, as best 30 shown in Figures 2 and 5, is connected by a universally jointed link 154 to an arm 155 on the slot piercing blade 76.

A cam 156 for operating the pierced flap folder, 40 as best shown in Figure 13, actuates a roller 157 on a lever 153. The lever 158 is pivoted on a bracket 159 carried by the I-beam 111 and the roller is held against the cam by spring 160, one end of which is connected to the lever and the other to a bracket 161 on the I-beam 111. The lever 158 is connected by means of a pivoted link 162 to one arm of a bell crank lever 163 which is pivotally mounted on a pin 164 carried by a projection 165 on the folding head, as best shown in Figure 5. The other arm of the bell crank 50 lever is connected by a universally jointed link 166 to an arm 167 fixed to the slotted flap folding element 181.

As best shown in Figure 9, a cam 168 for the hooked flap folder 83 engages a roller 169 on a lever 170. The lever is pivotally mounted on a bracket 171 carried by the I-beam 112. The roller is held in engagement with the cam by a spring 172, one end of which is connected to the lever and the other to bracket 173 on the I-beam 112. The lever 170 is connected by means of a pivoted link 174 to one arm of the bell crank 175 which is pivoted on the folding head by means of a pin 176. The other arm of the bell crank 175 is connected by means of a universally jointed link 176 to an arm 177 fixed to the hooked flap folding element 83. As previously mentioned, movement of the element 83 effects movement of the edge retaining element 88 by reason of the lost motion connection and spring 91.

As best shown in Figure 12, a cam 179 is provided for operating the hooked flap flattening element 93. This cam engages a roller 180 on a lever 181 which is pivotally mounted on a bracket 182 carried by the I-beam 112. The roller is held in engagement with the cam by spring 183.

one end of which is connected to the lever and the other to a bracket 184 carried by the I-beam 112. The lever 181 is connected by a pivoted link 185 to one arm of a bell crank lever 186, which is pivotally mounted on a bracket depending from the folding head by means of a pin 187. The other arm of the bell crank 186 is connected by a universally jointed link 188 to an arm 189 fixed to the flattening element 93.

The backup and spreader element 163 is operated by cam 190, shown in Figure 11. The cam engages a roller 191 on a lever 192 which is pivotally mounted on a bracket 193 carried by the I-beam 112. The roller is held in engagement with the cam by a spring 194, one end of which is connected to the lever and the other end to a bracket 195 on the I-beam 112. The lever 192 is connected by means of a pivoted link 196 to an arm 197 on the pivot 65 for the backup and spreader element 63.

The sequence of operations on a single carton blank is illustrated in Figures 19 through 32. Figure 19 is a plan view showing the position and direction of movement of the collapsed carton as it is ejected from the magazine onto the longitudinal plates 34 and 35. This occurs when the main feed slide 40 is in approximately the position shown in Figures 1 to 3 of the drawings. Thereafter, the feed slide is retracted and the spreader blade 46 passes under the ejected carton blank in a direction from right to left, as viewed in Figure 20, until it comes to its extreme retracted position shown in Figure 20. During such retraction, the springs 33 hold the carton blank down against the plates 34 and 35, except as it is lifted slightly by the spreader blade 46. As shown in Figure 20, when the spreader blade is in its fully retracted position, it just clears the lower flap *f* of the carton, but does not clear the upper flap *g*. Consequently, the upper flap is slightly lifted and the bottom edge of the spreader blade 46 lies above the flap *f* in position to enter the carton and partially spread it as soon as the main feed slide starts to advance.

This latter condition is illustrated in Figures 21 and 22, which show the position of the blade 46 in the carton and the partially spread carton as it starts to move forward under the influence of feed dog 42. The feed dog 42 on the main feed slide engages flap *f* and thus limits the degree of penetration of the spreader blade 46 to that shown in Figure 21.

As the carton is advanced, the side wall *d* of the carton engages and is lifted by the sloping block 51. Since the lower edge of the spreader blade holds the bottom wall *a* of the carton down against the plates 34 and 35, the lifting action of block 51 will further open or square the carton in the manner indicated in Figure 23. The initial spreading by blade 46 is essential to make the sloping block 51 effective because it stiffens the carton against bending transversely of its length and thus insures that block 51 will not simply bend the entire forward portion of the carton upwardly.

The feed dog 42 feeds the carton without interruption from its initial position opposite the magazine over the block 51 and into the final squaring device 52, which position is reached at the end of the forward stroke of the feed slide 40. The carton, when in that position, still engages the block 51. The squaring device 52 then operates to complete the squaring operation, as shown in Figure 24. The squaring device completes the squaring operation by forcing the corner of the carton defined by the juncture of walls *b* and *d*

toward the diagonally opposite corner defined by the juncture of walls *a* and *c*.

Thereafter, the feed slide 40 is retracted and again advanced. During the next advance stroke, feed dog 43 engages flap *f* of the carton and feeds it into the folding head 56. As soon as it enters the head, the top flap *g* is folded downwardly and the backup and spreading device simultaneously enters the opposite end of the carton as shown in Figure 25. The bottom flap *f* is then folded upwardly by member 70, as shown in Figure 26, thereby moving the backup plate 73 into position just inside of the flap *h*. In this position, the plate 73 supports flap *h* while the slot piercing blade 76 enters the slot in flap *h* and spreads it slightly, as shown in Figure 27, to facilitate subsequent entry of the hook. The flap *h* is then folded into position by member 81, as shown in Figure 28.

The final operations, which are illustrated in Figures 29 to 32, effect a closure of the hooked flap *j* and the insertion of the hook *m* into slot *k*. This operation is begun by an inward movement of flap closer 83. During the initial movement of closer 83, shown in Figure 29, the edge retainer 88 is moved in advance of closer 83 by spring 91. Consequently, the edge retainer overlies the top edge of the flap *j*. Since the axis of movement of the members 83 and 88 extends upwardly, forwardly, and inwardly the outer ends of members 83 and 88 swing downwardly and the edge retainer forces the upper edge of the flap *j* below the plane of the top of the carton, as shown in Figure 31, which illustrates the final position of members 83 and 88. During inward movement of the members 83 and 88, the edge retainer 88 engages the carton first and is held against the carton during the final movement of member 83 by spring 91, thus preventing the flap *h* from moving upwardly. In the final position of members 83 and 88, the top edge of flap *j*, from the upper corner of the carton to the notch adjacent the hook, is held against the carton by member 83, but the flap extends downwardly at such an angle that the point of hook *m* bears against flap *h* just below slot *k*. The lower edge of flap *h*, therefore, bulges outwardly, as indicated in Figure 31. At this time the inner surface of member 83 is flush with that of member 88, so that the edge retainer 88 no longer engages the top edge of the flap, but the flap is held against upward movement by reason of the fact that its upper edge abuts at an angle against the carton.

The bulged lower edge of the flap *h* is then flattened against the carton by member 93, as shown in Figure 32. This forces the flap to move upwardly past member 3 and causes the hook to enter the slot. It will be noted that the flattening of the bulge is effected progressively from the corner of the carton, due to the fact that the axis about which member 93 is pivoted is located in the transverse plane of the end of the carton. This insures that the flap will be folded at the exact corner of the carton. The instant that the hook begins its entry into the slot, members 83 and 88 are retracted so that they will not interfere with the final operation or cause flap *j* to wrinkle.

During the folding operations on the end of the carton, the main feed slide is retracted and, upon completion of the last operation, is ready to begin its forward stroke. At that time, the carton ejecting dog 38 on the end of pusher 41 is in the position illustrated in Figure 32, with the result that when the pusher advances the dog 38 will

engage and eject the folded carton. Spring 45 on the pivoted ejecting dog permits the dog to pivot downwardly so that it can be withdrawn beneath the carton which is being folded in the head. As the dog 38 ejects the carton, the backup and spreading member 63 is withdrawn.

It will be observed that one carton is completed and ejected on each cycle of movement of the feed slide 40, but that three cartons are being operated upon at once. The necessary correlation of the various operating movements is controlled by the shape and position of the cams on cam-shaft 10 and the main feed cam 96. Figures 1 to 17 of the drawings show the parts in the position they assume just before the main slide 40 completes its forward movement, during which it ejects a completed carton, feeds a squared carton into the folding head and a partially square carton into the squaring device 52. The backup device 63 has just started moving in. The operating cams are so arranged that the various elements of the machine are operated in the following sequence from the positions illustrated during one revolution of camshaft 10: (Where more than one operation appears under a single number, they are simultaneous.)

1. The magazine slide 29 starts in.
  2. The top flap folder 67 starts in.
  3. The squaring device 52 starts to close.
  4. The main slide 40 completes its forward movement and starts to retract. The bottom flap folder 70 starts up. The magazine slide 29 completes its feed stroke and begins to retract.
  5. Backup device 63 completes its inward movement. Top flap folder 67 completes its inward movement and starts to return.
  6. Squaring device 52 completes its closing movement.
  7. Top flap folder 67 completes its return movement.
  8. Bottom flap folder 70 completes its upward movement. Slot piercing blade 76 starts in.
  9. Slot piercer 76 starts to return. Bottom flap folder 70 starts down.
  10. Slotted flap closer 81 starts in.
  11. Hooked flap folder 83 starts in.
  12. Bottom flap folder 70 completes return movement.
  13. Pierced flap closer 81 completes inward movement.
  14. Hooked flap edge retainer 88 contacts carton.
  15. Hooked flap flattener 93 starts in.
  16. Hooked flap folder 83 completes inward movement.
  17. Hooked flap flattener 93 starts entry of hook m in slot k. Hooked flap folder 83 and edge retainer 88 start to return. Feed slide 40 completes return movement and starts to advance. Hooked flap flattener 93 completes entry of hook in slot and starts return.
  18. Backup device 63 starts out.
  19. Hooked flap folder 83 fully out. Hooked flap flattener 93 fully out. Slotted flap holder 81 starts out. Squaring device starts out.
  20. Slotted flap folder 81 fully out. Ejector dog 38 engages folded box.
  21. Backup device 63 fully out and starts return.
- It should be noted that the movements of many of the parts occur simultaneously and that the movements of the elements which effect the end closing operation overlap to the maximum degree possible without actual mechanical interference. Accordingly, the machine can be operated at high speed so that all of the end closing operations

occur almost simultaneously. A complete carton is ejected from the machine on each revolution of the camshaft 10.

It will be observed that all of the operating movements of the various mechanisms are positively effected by cams and linkage and that return movements of the elements are effected in most instances by springs. Since all of the cams are on a single camshaft, the proper sequence of operations may be readily adjusted by the relative rotative positions of the cams on the shaft. Once the cams are fixed in proper position the fact that the operating movements of the elements are effected by positive cam action makes it possible to operate the machine at very high speed, without danger of interference resulting from inertia effects. The return movements of the various elements, which are less critical, may be satisfactorily performed by springs which need only be of sufficient strength to complete the return movement within the time available for any given speed of operation. If desired, all of the cams may be formed as closed cams in the manner of cam 96, in which event both the operating and return movements of all elements will be positive.

It will be further noted that during each forward movement of the main slide three cartons in various stages of squaring or folding are advanced. Thus the feed dog 42 advances a carton from a position in front of the magazine to a position within the squaring device 52. The feed dog 43 at the same time feeds a squared carton from the squaring device 52 into the folding head 56 and the ejecting dog 38 ejects a completed carton from the folding head. Substantially all of the operating movements of the folding head occur during the return stroke of the slide.

While for convenience in locating the motor 3 and speed reducer 4, the machine is provided with a cross shaft 7 which carries the main feed slide cam 96, it will be obvious that since the shafts 7 and 10 rotate at the same speed, the cross shaft 7 may be omitted and the main feed slide cam 96 mounted on the camshaft 10. In that case, the main feed cam 96 would be formed as a face type cam, such as the cam 146.

An important feature of the machine resides in the fact that all of the operating elements of the folding head are carried by the head and are simple pivoted elements which effect their functions upon a predetermined annular movement about their pivoted supports. As the result of this arrangement, the entire head 56 may be removed from the machine by simply disconnecting the supporting arms 58 from the channels 18 and 19, and disconnecting the upper ends of the pivoted links 174, 128, 196, 185, 162, and 140 and the upper end of the lever 149 from the mechanism of the folding head. The head may then be replaced by a head constructed to fold cartons of a different size but which would otherwise be similar in construction to that illustrated. Since the movements of the various operating levers are effected by predetermined annular movement of each, the throw of the operating links 174, 128, 196, 185, 162, and 140 and the lever 149 will be the same for all sizes of cartons and, consequently, no changes need be made in the operating cams and levers associated with the camshaft 10 in order to adapt the machine to operate on cartons of different sizes. It will be understood, of course, that it may also be necessary to change the squaring plate 52 and the

magazine 26 so that they fit the new carton. The stroke of the magazine feeding slide may be changed in any desired manner, if necessary, as by relocation of the pin 105 on the bracket 106 and by shifting the cam engaging roller along the length of the lever 104. The machine thus may be readily adapted to operate on different size cartons, or machines for operating on two different sizes may be constructed to a large extent from identical parts.

While only one form of the invention is shown and described it will be understood that ordinary mechanical changes and substitutions may be made without departing from the spirit of the invention or the scope of the appended claims.

What is claimed is:

1. In a machine for closing the end of a carton having a pair of end flaps which fold toward each other on parallel lines, one of said flaps having a slot and the other a hook adapted to enter and interlock in the slot when the flaps are closed and having a third end flap adapted to fold at right angles to the other flaps, said machine having a pivoted member adapted to close the third flap, a backup plate carried by the pivoted member and adapted to move into a position parallel to and along one side of the slotted flap when the pivoted member is in flap closing position, a spreading blade adapted to enter the slot from the opposite side of said slotted flap and permanently displace one edge thereof out of the plane of the slotted flap while the backup plate is in said position, means operable thereafter to close the slotted flap and means for closing the

hooked flap and causing the hook thereon to enter the slot by movement of the point of the hook parallel to the plane of the slotted flap.

2. In a machine for closing the end of a squared carton having at least three end flaps, a removable folding head, pivoted elements on the head each adapted to close one flap, an operating cam for each element, and means operatively connecting the cams and elements, said connecting means being detachable from said elements to permit the substitution of a folding head adapted to operate on cartons of a different size.

HUGH F. CONSER.
